J. N. WARD.

Bayonet.

No. 18,876.

Patented Dec. 15, 1857.

UNITED STATES PATENT OFFICE.

JAMES N. WARD, OF NEW YORK, N. Y.

IMPROVEMENT IN BAYONET-FASTENINGS.

Specification forming part of Letters Patent No. 18,876, dated December 15, 1857.

To all whom it may concern:

Be it known that I, JAMES N. WARD, of the United States Army, of the city and county and State of New York, have invented a new and Improved Method of Securing Bayonets upon Muskets and other Arms; and I do hereby declare that the following is a full and exact description thereof, reference being had to the accompanying drawings, and to the letters of reference marked thereon.

The nature of my invention consists in attaching to the shank of the bayonet, by a hinge or rivet, a spring having a shoulder or projection on the under side, which, when in place on the gun, prevents the stud on the barrel from getting out of the bayonet-shank.

To enable others skilled in the art to make and use my invention, I will proceed to describe its construction and operation, reference being had to the drawings, in which the same letters in the two refer to the same parts in each.

Figure 1 is a view of the bayonet and improved fastening on the gun, and the spring open or not in place; Fig. 2, a side view of the spring detached.

A is a spring, having a hinge or pivot at o on the bayonet-shank B.

d is a projection on the under side of A, which serves to fill up a part of the slot F and render c, the stud on the barrel of the gun, immovable.

E is a flange by which the spring A is raised sufficiently to enable the part d to pass clear

of the slot in the bayonet-shank when the bayonet is to be "fixed" or "unfixed."

When the bayonet is to be attached or fixed to the gun, the spring A is raised slightly and turned to one side, as represented in Fig. 1, the shank of the bayonet is passed over the barrel of the gun, the stud c passing through the slot F to its place, as shown in the same figure. The spring is then returned to its position in the direction of the barrel, and the part d falls into the slot F, and is there held by the spring, forming, as it were, a continuous stud with c, thus rendering the bayonet immovable.

I do not claim, simply, the method of securing the bayonet by putting a catch below the stud, as a similar device has been long used in the ring-fastening, &c.; but

I claim—

1. The method of securing the bayonet by means of the spring A, constructed essentially as described, hinging or turning about some point on the bayonet or gun, for the purpose specified.

2. The right to attach the spring in such manner to the barrel or bayonet as shall prevent its turning farther than necessary, and to use any mechanical contrivance—such as studs, &c.—to effect the same object.

J. N. WARD.
